UNITED STATES PATENT OFFICE.

PERCY J. HINDMARSH, OF LINCOLN, NEBRASKA, AND JOHN W. MEAKER, OF EVANSTON, ILLINOIS, ASSIGNEES TO THE AMERICAN STEEL AND WIRE COMPANY OF NEW JERSEY, A CORPORATION OF NEW JERSEY.

TUBULAR FENCEPOST.

Application filed June 22, 1922. Serial No. 570,263.

To all whom it may concern:

Be it known that we, PERCY J. HINDMARSH and JOHN W. MEAKER, citizens of the United States, and residents, respectively, of Lincoln, in the county of Lancaster and State of Nebraska, and Evanston, in the county of Cook and State of Illinois, have invented certain new and useful Improvements in Tubular Fenceposts, of which the following is a specification.

This invention relates to fence posts and more particularly to metallic fence posts especially adapted for the construction of wire fences, and has for one of its objects the provision of a post of this character having a novel construction that will permit it to be driven into the ground, and will automatically spread at the lower end to form an anchor.

Still other objects and advantages such as simplicity, cheapness of manufacture, durability, and the general improvement of the art will be brought out more fully in the following specification and illustrated in the accompanying drawings, in which—

Figure 1 is a front elevation of a post constructed in accordance with this invention.

Figure 2 is a side elevation thereof.

Figure 3 is a rear elevation thereof showing the anchor opening or slot.

Figure 4 is an enlarged fragmentary detail elevation of a portion of a post showing the corrugated edge of the opening and manner of securing the staples in place.

Figure 5 is a cross sectional view on an enlarged scale showing the staple in locked position with the side walls of the post.

Figures 6 and 7 are enlarged detail views of the staples.

Figure 8 is an enlarged fragmentary view illustrating the manner in which the lower end of the post expands to form an anchor when being driven into the ground.

Referring particularly to the drawings, the numeral 2 designates side walls of the post which is preferably of hollow cylindrical steel construction formed with an open seam or slot 3 which extends the entire length thereof. The one longitudinal edge of the side walls paralleling the slot or opening 3 is corrugated to form alternate projections 4 and depressions 5. It will be understood, however, that both of the longitudinal edges of the side walls paralleling

the opening 3 may be corrugated if found as necessary or desirable.

A plurality of staples 6 are adapted to be driven into the opening 3 to hold the wire fencing 7 on the posts. The staples 6 are of the usual U-shaped design and are provided with oppositely tapered wedge like points 8 on their prongs or shanks 9. The prongs or shanks 9 of the staples are of greater diameter than the widest points of the opening 3. That is, they are of greater diameter than the opening 3 at the depressions 5 and are provided with notches 10 to the rear of the points 8, into which the edges of the side walls are adapted to spring when the staples are driven into the opening 3. The staples 6 are adapted to straddle the projections 4 when driven into the opening, thus preventing longitudinal or vertical displacement of the staples, while the notches 10 prevent horizontal displacement.

It will be readily seen from the above that the staples 6 form a positive attachment for the fencing that will not become accidentally displaced and yet one that may be removed when desired to remove or repair the fence by springing the post so as to spread the opening 3.

A short slot or opening 11 is provided in the wall of the post at a point diametrically opposite the opening 3, and extends from a point adjacent the bottom of the post upwardly to a point adapted to be below the ground level when the post is driven into position. The opening or slot 11 is adapted to weaken the post adjacent the bottom end so as to cause it to bulge outwardly when being driven into the ground due to the compression or packing of the earth within the post as it is forced into the ground, thus forming an anchor, as illustrated in Figure 8, which will serve to retain the post in position. If found desirable other slots similar to slot 11 may be formed adjacent the bottom of the post to further weaken that portion of the post and therefore cause it to bulge to a greater diameter than with one slot and with less force than necessary when only one slot is used.

The advantages of this invention will be readily apparent. It provides a cheap post of all metal construction which may readily be placed in position without the necessity of digging holes, it is provided with means for anchoring it in position, and it is pro-

vided with means for detachably securing the wire fencing thereto.

We claim—

1. A hollow steel fence post having a longitudinal opening extending from end to end thereof, and at least one other longitudinal opening extending upwardly from adjacent the bottom end of said post to a point adapted to be below the ground level, and one edge of the side wall of said post paralleling said first named opening being provided with a series of alternate projections and depressions.
2. A hollow cylindrical metallic fence post having a longitudinal opening extending from end to end thereof, and at least one other longitudinal opening extending upwardly from adjacent the bottom end of said post to a point adapted to be below the ground level, said last named opening being diametrically opposite said first named

opening, and one edge of the side wall of said post paralleling said first named opening being provided with a series of alternate projections and depressions, substantially as and for the purpose described.

3. A hollow metallic fence post having a longitudinal opening extending from end to end thereof, said opening being adapted to receive and hold wire fence securing members over a portion of its length, and at least one other longitudinal opening extending upwardly from adjacent the bottom end of said post to a point adapted to be below the ground level, said openings cooperating to permit the walls of said post to spread when the post is driven into the ground, thus forming an anchor.

In testimony whereof we have hereunto set our hands.

PERCY J. HINDMARSH.
JOHN W. MEAKER.
